UNITED STATES PATENT OFFICE

2,411,271

AIRCRAFT PROPELLER

William I. Jackson, Orange, Calif.

Application August 26, 1943, Serial No. 500,083

2 Claims. (Cl. 170—168)

1

My invention relates to a propeller for aircraft such as airplanes, helicopters, dirigibles and the like, and the principal object of my invention is, to provide a propeller which in structure, combines fan blades and a ring or rim having air passageways, in order to develop extremely high pulling or lifting power when rotated at high speed.

A further object of my invention is to provide a propeller of the character referred to, wherein the blades or vanes, in addition to being inclined in cross section, are inclined lengthwise so their inner ends, which are connected to a hub, are positioned forwardly of the outer ends of said blade and the rim or ring to which said outer ends are connected.

Further objects of my invention are, to construct the propeller in a single piece, by casting methods or otherwise, and to embed in the periphery of the rim or ring portion of the propeller, a member such as a steel cable, in order to counteract and resist bursting strains when the propeller is rotated at high speeds.

With the foregoing and other objects in view, my invention consists of certain novel features of construction and arrangement of parts, which will be hereinafter more fully described and claimed and illustrated in the accompanying drawing, in which:

Fig. 1 is a front elevation of the propeller.

Fig. 2 is a plan view.

Fig. 3 is an enlarged cross section taken on the line 3—3 of Fig. 1.

Fig. 4 is an enlarged section taken on the line 4—4 of Fig. 1.

Fig. 5 is an enlarged cross section taken on the line 5—5 of Fig. 1.

Fig. 6 is a cross section of the peripheral rim of the propeller and showing a reinforcement therefor.

Referring by numerals to the accompanying drawing which illustrates a preferred embodiment of my invention, 10 designates a hub, with which is formed integral, the inner ends of a plurality of radial blades 11 which are correspondingly inclined in cross section, also inclined lengthwise so that their outer ends occupy a plane rearwardly of their inner ends and the hub.

Thus the propeller is substantially dish shape, with its convex face or side forwardly presented. The rim or ring which connects the outer ends of the blades includes a peripheral rim number 12, which is substantially lozenge shape in cross section with smooth convex faces and fairly sharp front and rear edges, thus providing a streamlined effect.

2

Formed integral with and projecting inwardly from rim 12, midway between its front and rear edges, is a web or flange 13 and the outer ends of blades 11 are formed integral with this web and with rim 12 by means of outer walls 14, which connect the outer ends of said blades with said rim and inner walls 15 which connect the blades, inwardly from walls 14, with the inner portion of web 13.

These walls 14 and 15 are disposed transversely of the blades 11 and formed through web 13 between said walls, and beneath the outer end of each blade is an air passageway such as 16.

Formed through web between the openings 16 are similar openings to provide air passageways 17, and overlying each of said passageways is an integral plate or wall 18, which is inclined lengthwise to correspond with the transverse inclination of the blades 11.

Connecting the inside edges of the inclined plates 18 with web 15 along the inner edges of the openings 17 are integral walls 19, and the outer edges of said inclined plates are integrally connected to the inner face of rim 12 (see Fig. 5).

During operation the propeller is rotated at high speed, and those portions of the blades inwardly from the rim will function in the usual manner and force a heavy column of air rearwardly through the rim or ring. At the same time the outer ends of the blades which are inclined, and the inclined plates 18, will force air through openings 16 and 17 in the rim so as to produce a tubular column of air surrounding the column driven rearwardly by the inner portions of the blades, thus producing a high degree of pulling or lifting force upon the aircraft with which the propeller is associated.

To reinforce the rim portion of the propeller and provide resistance to bursting strains developed while said propeller is rotated at high speeds, a member, preferably a steel cable such as C, may be embedded in the rim member 12 (see Fig. 6).

Where larger sizes of my improved propeller are built for use on large helicopters, said propellers may take the shape of an umbrella or parachute and reinforced by guy rods or wires extending from the hub to the outer portion of the rim.

Propellers constructed in accordance with my invention, and in smaller sizes, may be advantageously employed for the propulsion of boats, also in rotary pumps, compressors, impellers and the like.

Thus it will be seen that I have provided a propeller which is simple in structure, inexpensive of

manufacture and very effective in performing the functions for which it is intended.

It will be understood that minor changes in the size, form and construction of my improved propeller may be made and substituted for those herein shown and described without departing from the spirit of my invention, the scope of which is set forth in the appended claims.

I claim as my invention:

1. In an airplane propeller, a hub, a series of blades projecting radially from said hub, which blades are inclined lengthwise and in cross section, a peripheral ring integrally connected to the

outer ends of said blades, which ring is lozenge shape in cross section and being offset rearwardly from said hub, a continuous flange projecting inwardly from said ring between its front and rear ends, the inner edge of which flange is secured to said blades inwardly from their ends, and there being spaced openings formed in said flange.

2. An airplane propeller as set forth in claim 1, with inclined plates integral with said flange in front of the openings therein.

WILLIAM I. JACKSON.
